UNITED STATES PATENT OFFICE.

AXEL FOLKE CARLSON, OF CAMBRIDGE, MASSACHUSETTS, ASSIGNOR TO THE REECE
BUTTON HOLE MACHINE COMPANY, OF BOSTON, MASSACHUSETTS, A CORPORA-
TION OF MAINE.

SEWING MACHINE.

Application filed September 5, 1925. Serial No. 54,787.

This invention relates to sewing machines of that type having a needle operating above the work and making penetrating thrusts through the work, and two loopers situated beneath the work each having a looper spreader associated therewith, said loopers operating alternately to engage the loops of needle thread thrown out from the needle and the spreaders co-operating 10 with the loopers to spread each loop of needle thread and place it in position to be entered by the needle at its next penetrating thrust.

In some sewing machines of this type, and especially machines which are designed to sew buttonholes, the needle is provided with a jogging movement so that alternate thrusts of the needle are at the slit of the button-hole and the other thrusts are through the 20 work at a distance back from the slit, and the loopers and spreaders are carried by a rotatable turret which is situated beneath the work.

My invention relates particularly to a sewing machine of this type and one feature of the invention is the provision of novel means for actuating the loop spreaders by means connected to and actuated by the needle jogging mechanism. This not only simplifies the construction but ensures proper timing of the spreaders.

Other features of my invention relate to a novel mechanism for actuating both the loopers and the spreaders which is especially adapted for high speed operation, and also to a novel construction by which the amplitude of movement of the loopers and spreaders may be varied.

In order to give an understanding of the invention I have illustrated in the drawings a selected embodiment thereof which will now be described after which the novel features will be pointed out in the appended claims.

Fig. 1 of the drawings is a side view of a sewing machine embodying my invention with the cover plate removed to better show the spreader-actuating mechanism;

Fig. 2 is an under side view illustrating part of the device for actuating the looper and the spreader;

Fig. 3 is a fragmentary view illustrating the loopers and spreaders and their operating mechanism;

Fig. 4 is a sectional view showing the

adjustment for varying the amplitude of movement of the loopers;

Fig. 5 is a view of the looper spreader;

Fig. 6 is a top plan view of the looper carrier and looper spreader with one of the 60 loopers and its looper spreader omitted, the other looper and its looper spreader being shown in the position they assume while entering the loop of needle thread;

Fig. 7 is a similar view showing the 65 spreader in its position for spreading the loop.

In the sewing machine illustrated in Fig. 1, 1 indicates the base frame which carries the head 2 in which is mounted the vertically reciprocating needle bar 3 carrying the needle 4. The needle bar, which is reciprocated by any suitable mechanism, such for instance as that shown in Patent No.

1,437,847, December 5, 1922, but which mechanism has been omitted from the present drawings in order not to confuse the same, has a jogging movement in timed relation with its reciprocation. The means herein shown for jogging the needle is also similar 80 to that illustrated in the above-mentioned Patent No. 1,437,847. This needle jogging mechanism comprises a lever 5 pivotally mounted on a shaft 6 and flexibly connected to a sleeve 7 through which the needle bar reciprocates so that rocking movement of the lever 5 will oscillate the sleeve 7 in a vertical direction. Such oscillatory movement of the sleeve operates to give the needle bar its side jogging movement all as set 85 forth in the above-mentioned patent. Inasmuch as this particular mechanism for jogging the needle is not new with me I have not deemed it necessary to further illustrate it.

The lever 5 is actuated from a cam 8 which is mounted on a drive shaft 9. This cam operates between the arms 10 of a forked member 11 which is pivoted to the head 2 at 12 and one arm 10 of the fork 100 is connected to the lever 5 through a link connection 13. The rotation of the cam 8 will, of course, oscillate the forked member 11 and its oscillation is transmitted to the lever 5 through the link 13 all as set forth 90 in the above-mentioned patent.

The two loopers are indicated at 14 and 15, these being mounted on an oscillatory looper carrier 16 which is pivotally mounted at 17 on a turret 18, said turret being 110

2
mounted for rotation about a vertical axis in bearings 19 formed in the portion 20 of the frame, all as usual in sewing machines of this type. The looper spreaders are indicated at 21 and 22.

5 Each spreader is provided with a stem or shank 81 which is pivotally mounted in the looper carrier 16 so that each spreader can swing from the position shown in Fig. 10 6 to that shown in Fig. 7. Each spreader is provided with a tail 82 which is acted upon by a spring 83 that normally tends to hold it in the closed position shown in Fig. 15 6. The spreaders receive their loop-spreading movement by means of a spreader 23 which is a forked member such as shown in Fig. 5 and is pivoted on the turret coaxially with the looper carrier 16. This spreader actuator has an oscillatory movement by 20 means presently to be described and it is provided with the two bevel or cam faces 84 that engage the tails 82 of the spreaders as the spreader actuator oscillates whereby the spreaders are swung from their closed 25 to their open position or from the position shown in Fig. 6 to that shown in Fig. 7.

It will be understood that each spreader is in the position shown in Fig. 6 when the corresponding looper enters the loop of 30 needle thread and that after the loop of needle thread has thus been entered the spreader actuator is operated as shown in Fig. 7 to actuate the spreader and thereby spread the loop of needle thread, said looper 35 and spreader carrying the loop into position to be entered by the needle on its next penetrating thrust.

40 85 indicate hold downs which operate to retain the looper spreaders in position, said hold downs also acting as a stop for the spreaders. A more complete description as to the manner in which the loopers and spreaders operate in forming the stitches will be found in United States Patent No. 45 862,238, Aug. 6, 1907, to which reference may be had.

The looper carrier is oscillated by means of the vertical reciprocation of a sleeve 24 which is mounted in the turret and which is given its vertical reciprocation by means 50 presently to be described. This sleeve has a collar 25 fast thereon which is connected by a link 26 to an arm 27 extending laterally from the looper carrier whereby vertical reciprocation of the sleeve 24 will oscillate the looper carrier thus causing the loopers alternately to engage the loops of needle thread. The looper spreader is given its oscillation to actuate the spreaders by means 55 of the vertical oscillation of a spindle 28 which reciprocates vertically through the sleeve 24, said spindle having a collar 29 thereon which is connected by a link 30 to an arm 31 extending from the looper spreader.

The parts thus far described are or may be all as usual in devices of this nature and their operation will be understood by reference to the above-mentioned patents to which may be added Patent No. 1,352,280.

One feature of my present invention relates to a novel means for actuating the spindle 28 and thereby the spreaders. This is accomplished herein by means which are connected to and are actuated by the needle jogging mechanism. The spindle 28, which 70 extends entirely through the sleeve 24, is pivotally connected at its lower end to an arm 32 rigid with a shaft 33, the latter being journalled in suitable bearings 34 and 35 that are secured to the frame. This shaft 75 33 also has another arm 36 rigid therewith which is connected by a link 37 to one arm 38 of an elbow lever 39 which is pivoted to the frame at 40. The other arm 41 of this elbow lever is connected by the link 42 80 85 to the forked member 11 and, therefore, the oscillation of said forked member 11 will oscillate the elbow lever 38 and through the link 37 will oscillate the shaft 33. The rocking movement of the shaft 33 will reciprocate the spindle 28 as will be obvious thereby giving the spreader actuator its required movement. By means of this construction the looper spreaders are always operated in 90 timed relation with the movement of the needle and the operating parts are of a construction which is conducive to high speed operation as all long levers, such as found in the above-mentioned patents, are eliminated and the parts which have a bodily movement 100 are relatively light.

105 The needle jogging mechanism is provided with the usual adjustment for adjusting the extent of the jogging movement of the needle, this adjustment being in the nature of a slot 53 in the lever 5 in which the end of the link 13 is adjustably secured.

In order to produce satisfactory stitching it is desirable to spread the loop to a greater extent as the jogging movement of the needle is increased and I have, therefore, provided herein means whereby the amplitude of movement of the spreader actuator may be varied thereby to produce a greater or less 110 loop-spreading effect. This is accomplished by an adjustable connection between the oscillatory forked member 11 and the elbow lever 39. It will be noted that the link 42 is adjustably connected to the arm 41 of the elbow lever 39 by means of the slot 63 115 formed in said arm in which the end of the link 42 is adjustably secured. When the needle jogging mechanism is adjusted to make a stitch having a long bight then a corresponding adjustment may be made in the connection between the link 42 and the arm 41 of the elbow lever so as to give the loop 120 spreaders a greater loop-spreading move- 125

ment and similarly when the jogging movement is adjusted to form a stitch with a relatively short bight a reverse adjustment may be effected in the connection between the link 42 and arm 41 of the elbow lever 39.

For operating the sleeve 24 by which the looper carrier is actuated I have provided a second rock shaft 43 which is journalled in suitable bearings 44 and which has fast thereon at one end an arm 45 that is pivotally connected to the lower end of the sleeve 24. The other end of said rock shaft has an arm 46 fast thereto to which is connected a link 47. This link is provided at its upper end with a roll 48 operating in a cam groove 49 formed in a cam member 50 which is mounted on the shaft 9. In order to guide the upper end of the link 47 and hold it in its proper position laterally said link is forked as shown at 51, the fork of the link embracing a hub 52 formed on the shaft 9 and thereby holding the upper end of the link from lateral movement. The cam groove 49 will reciprocate the link 47 vertically thereby rocking the shaft 43 and the rocking movement of the shaft will be communicated to the arm 45.

The throw of the cam groove 49 is relatively slight and in order to give the sleeve 24 the proper amplitude of movement I propose to give the shaft 43 an angular position as shown in Fig. 2 so that the arm 45 will be longer than the arm 46. This increased length of the arm 45 serves to give the sleeve 24 a greater amplitude of movement than the link 47 has and thus the required oscillating movement of the looper carrier may be secured with a cam having a small throw.

It is desirable to be able to vary the amplitude of oscillation of the looper to correspond to the bight of the stitch or, which is the same thing, the extent of jogging movement of the needle and I accomplish this herein by providing an adjustable connection between the link 26 and the arm 27. The arm 27 is shown as having an undercut slot 58 therein and the link 26 has pivoted in its upper end a sleeve 54 through which extends a bolt 55, the head 56 of which occupies the slot 58. This bolt is provided with a clamping nut 59 by which the sleeve 54 is clamped in adjusted position. By loosening the nut 59 the pivotal connection between the link 26 and the arm 27 may be adjusted thereby to vary the amplitude of movement of the looper carrier.

I claim.

1. In a sewing machine having a needle operating above the work and two loopers and their looper spreaders operating beneath the work, the combination with said needle, loopers and spreaders, of needle jogging mechanism, and means actuated by the needle

jogging mechanism for operating the looper spreaders.

2. In a sewing machine, the combination with a needle, of two loopers situated beneath the work, means to actuate the loopers, a looper spreader for each looper, means to give the needle a jogging movement, and means to actuate the looper spreaders by the needle jogging mechanism.

3. In a sewing machine, the combination with a needle, of two loopers situated beneath the work, means to actuate the loopers, a looper spreader for each looper, a cam-actuated vibratory member for giving the needle a jogging movement, and means actuated by said member to operate the spreaders.

4. In a sewing machine, the combination with a needle arranged to penetrate the work from above, of two loopers co-operating with said needle, a looper spreader for each looper, two rock shafts, means to oscillate said rock shafts, and connections for operating the loopers from one rock shaft and the looper spreaders from the other rock shaft.

5. In a sewing machine, the combination with a needle adapted to penetrate the work from above, of an oscillating looper carrier situated beneath the work, two loopers carried by said looper carrier, a looper spreader for each looper, a rock shaft for actuating the looper carrier, a second rock shaft for operating the looper spreaders, means for giving the needle a jogging movement, means for oscillating the first-named rock shaft, and means actuated by the needle jogging mechanism for oscillating the second-named rock shaft.

6. In a sewing machine, the combination with a needle, of two loopers situated beneath the work, means to actuate the loopers, a looper spreader for each looper, means to give the needle a jogging movement, and means to actuate the looper spreaders by the needle jogging mechanism, both the needle jogging mechanism and the means for actuating the looper spreaders being adjustable to vary the extent of both the jogging movement of the needle and of the loop-spreading movement of the spreaders.

7. In a sewing machine, the combination with a needle, of two loopers situated beneath the work, means to actuate the loopers, a looper spreader for each looper, a cam, means actuated thereby to give the needle a jogging movement, other means also actuated thereby to actuate the looper spreaders, each of said last-named means being adjustable, whereby the amplitude of the needle jogging movement and the extent of the loop-spreading movement may be varied.

In testimony whereof, I have signed my name to this specification.

AXEL F. CARLSON.
